(57) **CLAIM**

The ornamental design for a bottle splash guard, as shown and described.

DESCRIPTION

FIG. 1 is a side elevation perspective view of a bottle splash guard showing my new design in a position of use fitted into a bottle drawn in broken lines, taken from above and off-center;

FIG. 2 is a side elevation perspective view of the bottle splash guard removed from the bottle, taken from above and off-center from the bottle splash guard;

FIG. 3 is a perspective view taken from above and off-center from the bottle splash guard of FIG. 2;

FIG. 4 is a top plan view thereof;

FIG. 5 is a side elevation view thereof;

FIG. 6 is a bottom plan view thereof; and,

FIG. 7 is a cross-sectional view taken in the direction of line 7-7 of FIG. 6.

The broken lines showing a bottle in FIG. 1 depict environment and form no part of the claimed design.
